Fig. 3

Fig. 4

Fig. 5

FIGURE 1 is a perspective view of a pry bar embodying my new design;

FIG. 2 is a plan view thereof;

FIG. 3 is a side elevational view thereof, the side opposite being substantially a mirror image thereof;

FIG. 4 is an elevational view of one end thereof; and

FIG. 5 is an elevational view of the end thereof opposite that shown in FIG. 4.

The characteristic features of my design reside in the configurations of the merging upper and lower handle flanges with the end blades, as best shown in FIGURE 1.

I claim:

The ornamental design for a pry bar, substantially as shown and described.
